UNITED STATES PATENT OFFICE

133,616

DESIGN FOR A MERCHANTISE SHELF DISPLAY DEVICE

Richard Freedman, New York, N. Y.

Application June 5, 1942, Serial No. 107,141

Term of patent 14 years

To all whom it may concern:

Be it known that I, Richard Freedman, a citizen of the United States, residing at New York, in the county of New York and State of New York, have invented a new, original, and ornamental Design for a Merchandise Shelf Display Device, of which the following is a specification, reference being had to the accompanying drawing, forming part thereof,

I claim:

The ornamental design for a merchandise shelf display device, as shown.

RICHARD FREEDMAN.
